(57) **CLAIM**

The ornamental design for a pillow, as shown and described.

DESCRIPTION

FIG. 1 is a front, top, and right-side perspective view of a pillow according to a fourth embodiment of the present invention;
FIG. 2 is a front elevational view of the pillow shown in FIG. 1;
FIG. 3 is a rear elevational view of the pillow shown in FIG. 1;
FIG. 4 is a right-side elevational view of the pillow shown in FIG. 1;
FIG. 5 is a left-side elevational view of the pillow shown in FIG. 1;
FIG. 6 is a bottom plan view of the pillow shown in FIG. 1; and,
FIG. 7 is a top plan view of the pillow shown in FIG. 1. The surface shading illustrated in the drawings is provided merely to highlight the contour of the design; it is not intended to be illustrative of texture or gloss. The dot-dash broken lines, which are immediately adjacent to shaded areas, define the bounds of the claimed design, while the dashed broken lines are directed to environment; broken lines form no part of the claimed invention.
